UNITED STATES PATENT OFFICE

GEORGE W. RIENKS, OF DENVER, COLORADO

SCREENING DEVICE

Application filed November 11, 1929. Serial No. 406,456.

This invention relates to screening apparatus of the grizzly type, particularly adapted for the separation of dirt and other refuse matter from sugar beets.

Apparatus of this character, in which the beet roots as they are lifted from the ground, travel over a field of rotating agitative parts, has been disclosed in my application for Patent Serial No. 119,017, filed June 28, 1926, and it is an object of the present invention to provide at the discharge end of the said field an auxiliary means for the final separation of trash and leaves associated with the beet roots.

A further object of the invention is to provide said auxiliary separating means in the form of one or more rollers rotating in a direction opposite to that of the rotary members of the screening apparatus and disposed relative to the screen proper to cause the beets to fall across their surfaces separate from the lighter refuse that follows the rollers in their rotary motion.

Another object is to augment the final separation by means of the roller or rollers, by the provision of an air blast.

Still another object of the invention resides in providing against breakage or deformation of the rotating agitating parts by mounting them so as to be relatively movable in lateral direction, and a further object is to so arrange the parts upon their common shafts, as to eliminate large valleys in which small beets or parts of beets can lodge and to increase the agitative effect of the screen upon the beets.

With the above and other objects in view my invention comprises the combinations and arrangements of devices hereinafter to be described and illustrated in the accompanying drawings in the several views of which like parts are similarly designated and in which,

Figure 1 represents a sectional elevation of a screening apparatus to which the improvements have been applied,

Figure 2, a fragmentary plan view of the same,

Figure 3, a fragmentary elevation looking in the direction of the arrow 3 in Figure 2,

Figure 4, a perspective view of an end of

a separating roller showing a modification in the construction thereof,

Figure 5, a plan view of the discharge end portion of the screening apparatus, showing a modification in the construction of the separating element at the end of the screen,

Figure 6, a section taken on the line 6—6, Figure 5,

Figure 7, an enlarged section on the line 7—7, Figure 5, showing the modified arrangement of the agitating members whereby large valleys are eliminated, a more effective agitative action is produced, and breakage or deformation of the parts by the passage of rocks and other hard foreign objects, are prevented, and

Figure 8, a section along the line 8—8, Figure 7.

A rectangular frame including parallel side bars 5, supports the screening mechanism 70 which as shown in the drawings, comprises a series of agitating units connected to rotate in unison in one and the same direction.

Each unit consists of a shaft 6 rotatably supported in boxes 7 on the side bars of the frame, and agitating members which are carried by the shafts.

The body portions of the shafts are squared or otherwise angled for the support of the agitating members in rotative conjunction therewith, and the end portions of the shafts are round for their rotation in the respective boxes.

The shafts are connected for synchronous rotation in one direction and at a uniform speed by sprocket chains 8 which through the medium of sprocket wheels keyed on the ends of the shafts projecting beyond one of the said bars of the frame, transmit the movement of each shaft to the next following one in successive order.

The agitating members are each composed of a hub 9 having a squared opening corresponding with the squared portion of the respective shaft, and slightly resilient curved arms or spokes 10 which are set in equidistant apertures of the hub.

The arms on each hub curve in the same direction and are equidistantly spaced and the members are mounted in series on the

shafts between the side bars of the frame with their hubs in end-to-end relation.

Between the end members of the series and the side bars of the frame are fillers 12 to 5 hold the series against sideways displacement.

The series of agitating members on each shaft are staggered with relation to those on immediately adjoining shafts so that their 10 arms overlap one another.

The hubs of the members are proportioned so that the arms of the members are close together and the shafts are placed apart at distances which permit the arms on one shaft 15 to closely approach the hubs on the other during rotation of the shafts.

The agitating members thus arranged, present a field over which the beets may travel from one end to the other, broken by 20 the narrow spaces between the lapping arms of the members and between the arms of the members and the hubs of adjacent members.

These spaces are so narrow as to prevent the passage of beets or portions of beets there- 25 by permitting of an unobstructed movement of the beets from one end of the separator to the other, it being the main purpose of the machine to remove from the beets, the trash that was fed with the roots and the dirt that 30 adhered to the roots as they were pulled from the ground.

In the treatment of beets of varying sizes, including small roots or portions of roots, the screen units should be formed so as to 35 eliminate large valleys in which the smaller parts might lodge.

With this object in view, it has been found advantageous to stagger the agitating members of each unit by advancing each alternate 40 member on the shaft, a distance equal to one half the space between the curved spokes of each member, as best shown in Figures 7 and 8 of the drawings. This arrangement places the spokes of the alternate members in an 45 alignment between the alignments of the spokes of the other member thereby eliminating the large lodging spaces of the units of the ordinary construction, illustrated in Figure 2.

50 The staggered arrangement of the agitating members of the units moreover, increases the agitative effect upon the beets by a more rapid dancing movement of the same as they pass from one end of the screen to the other.

55 The agitating members, as shown in Figures 5 to 8 of the drawings, are fitted loosely on their respective shafts and are slightly spaced apart so that they may move laterally in a wabbling motion.

60 The object of this arrangement is to permit the agitating members to give or yield when rocks or other hard foreign objects fed onto the screen with the beets, pass between the resilient spokes or arms.

65 Breakage and bending of the spokes, a fre-

quent occurrence in screens in which the agitating members are immovably fixed on their shafts, are by the improved arrangement, reduced to the minimum.

The beets are fed onto the separator by a 70 belt 13 on a roller 14 which is supported in boxes 15 at the feed end of the frame.

The roller is rotated in the direction of the arrow A by gear wheels 16 and 17 which connect it with a power shaft 18, and the movement of the roller shaft is transmitted to the shaft of the adjoining unit of separating members by means of a sprocket chain 19. This connection and the connections between the shafts of the various units will cause all 75 of the units to rotate synchronously in the same direction with the feed roller as indicated by the arrows B.

At the discharge end of the separator, is located the auxiliary separating unit which has 80 for its object to separate from the beets any remaining trash and leaves so that the roots may be delivered to the loading conveyor 20 in a substantially clean condition.

The clean separation of dirt and refuse 85 matter from sugar beets is of paramount importance since it is customary to weigh this dirt and refuse and deduct their weight from that of the load fed on to the separator, whereby to establish the net weight of the beets 90 and their value at a pre-established rate per ton.

The auxiliary separating element as shown in Figures 1 and 2 of the drawings, comprises a roller 21 which in the operation of the machine rotates in a direction opposite to that of the agitating units as has been indicated by the arrow C.

The roller supported in bearings 22 on the side bars of the frame, is to this end connected with the shaft of the rearmost agitating unit by gear wheels 23 and 24.

The roller is disposed beneath the field of travel of the beets established by the agitating units, in a position so that beets passing across the delivery end of the field, engage the surface of the roller slightly beyond the vertical plane of its axis of rotation.

The roller is disposed relative to the last agitating unit so as to leave a space 25 too narrow to permit of the passage of the beets or portions thereof, and owing to the above-described arrangement of the roller, the beets will fall across the surface thereof in the same direction in which they were delivered from the screen, notwithstanding the rotary movement of the roller in the opposite direction, while leaves, trash and other light matter will follow the movement of the roller and pass through the space between the roller and the end of the separator.

All of the refuse separated from the beets is received in a hopper 26 which conveys it to wagons or other receptacles placed beneath the machine.

The final separation of the leaves and trash from the beets may be aided and expedited by a blast of air directed toward the space 25 between the roller and the separator by means of a nozzle 27.

It has been found advantageous to roughen the surface of the roller so that the light trash and leaves may better adhere to the same in its rotary motion.

10 This roughening of the roller may be done in any suitable manner and in an extreme form thereof, the surface of the roller may be studded as shown at 28 in Figure 4. The knobs or studs may be formed of the heads of rivets or nails driven into the roller.

15 In case one roller is not sufficient to effect a clean separation of the leaves and trash from the beets, the separative action may be repeated by the provision of a plurality of 20 rollers in spaced succession, as shown in Figures 5 and 6.

The rollers 21 and 21a are connected to all move in the same direction by sprocket chains 29.

25 The beets discharged from the screen fall progressively from one roller onto another and during each progression the leaves and trash fall through the spaces between the rollers so that when the beets are finally delivered to the loading conveyor all foreign matter has been separated therefrom.

It is of importance that the beets engage the surfaces of the roller or rollers at the right point so as to continue their movement 35 in a direction contrary to the direction in which the rollers move about their axes, for which reason a vertical adjustment of the roller or rollers is desirable. Such adjustment has been illustrated in Figures 5 and 6 40 in which the rollers 21 and 21a are mounted for rotation on two parallel arms 30 which are rotatably supported upon the shaft of the last agitating unit of the screen.

45 One of the arms has an outwardly extending lug 31 provided with a bearing 32 for the rotary support of a screw 33, which screw cooperates with a pivoted nut 34 on the frame of the machine.

50 It will be seen that by rotation of the screw, the series of rollers may be raised or lowered whereby to adapt the final separating element for the separation of trash and leaves from sugar beets delivered across the end of the screen, under different conditions.

55 The means for adjustment of the rollers, as shown, may of course be varied within the scope of the invention.

In the operation of the machine, the frame is preferably inclined lengthwise upon a 60 suitably constructed base and the hopper is placed beneath the field of agitating members as shown and hereinbefore described.

65 By power applied to the driving shaft, all the series of agitating members are caused to rotate in one direction and preferably at equal

speed while the roller or rollers of the auxiliary separating element rotate simultaneously in the opposite direction.

The beets fed onto the field of agitating members by the belt 13, are engaged by the curved arms of the agitating units and propelled toward the opposite end of the machine in a jiggling motion.

70 The constant agitation of the beets by their dancing motion as they move across the revolving arms cleans them of most of adherent dirt and most trash, and any leaves or trash remaining after the beets have been discharged across the last unit of the agitator, is separated from the roots by the auxiliary separating element consisting of the oppositely moving roller or rollers, as hereinbefore explained. The air blast may be resorted to if necessary so that a complete and clean separation of practically all of the dirt 75 and trash from the beets may be obtained.

80 The spacing of the agitating units from each other and the sides of the frame and the spacing of the rollers 21 and 21a from each other and from the last agitating unit 85 are important factors since they prevent beets or any parts thereof to be discharged with the leaves and trash.

85 The beets travel loosely and freely across the field of agitating arms and the rollers and there is no obstruction whatsoever to their continuous progression from the feed end of the machine to the point of final discharge. Loss of beet root is thus completely avoided which is of particular advantage 90 when, as often occurs, the tails of the beets are broken off the body parts or the beets are otherwise fractured in pulling, topping or transportation.

95 In the treatment of small or broken beets, the staggered arrangement of the agitating members of the several units, as illustrated in Figures 5 to 7, prevents the spaces between the spokes of the members from being clogged, and the loose mounting of the agitating members shown in the same views, prevents breakage or bending of the spokes by foreign objects accidentally fed onto the screen with the beets.

100 The continuous unobstructed propulsion of the beets brings the capacity of the machine to the maximum and permits of the beets being treated in large quantities in a comparatively short period of time. Only sufficient power is required to overcome the frictional resistance of a loosely carried load aside from the friction between the contacting parts of the moving parts of the machine and the bearings in which they are supported.

105 The resiliency of the teeth of the agitating members prevents injury to the beets and it also aids in the ejection of rocks and other obtrusive objects.

110 It is to be understood that while the machine, as shown and described, is particularly 115

adapted for the separation of dirt and refuse matter from sugar beets, it may also be used to advantage in screening coal and other materials.

5. What I claim and desire to secure by Letters Patent is:

1. Apparatus for screening sugar beets, comprising a movable screening element, movable in a direction opposite to that of said screening element, and movable constantly in one direction only to effect a propulsion and screening of the beets, an auxiliary separating element disposed to intercept beets discharged from the screening element and adapted for the separation of trash from the beets, and one hopper disposed to receive dirt and trash separated from the beets by the screening element and the auxiliary separating element, the auxiliary separating element being adapted to deliver beets received from the screening element, outside the hopper.

2. Apparatus for screening sugar beets, comprising a movable screening element movable constantly in one direction only to effect a propulsion and screening of the beets, and an auxiliary separating element including a roller rotating in a direction opposite to that of the movement of the beets from the screening element, and disposed to intercept upon its peripheral surface the beets discharged from the screening element for the separation of trash from the beets, the roller being spaced from the discharge end of the screening element for the passage of the trash exclusive of the beets or parts thereof.

3. Apparatus for screening sugar beets comprising a screening element, and an auxiliary separating element including a roller rotating in a direction opposite to that of the movement of the beets from the screening element, and disposed to intercept the beets discharged from the screening element for the separation of trash from the beets, the roller being spaced from the discharge end of the screening element for the passage of the trash exclusive of the beets or parts thereof, and a nozzle disposed to direct an air blast toward said space.

4. Apparatus for screening sugar beets, comprising a screening element, movable constantly in one direction only to effect a propulsion and screening of the beets, and an auxiliary separating element including a peripherally roughened roller rotating in a direction opposite to that of the movement of the beets from the screening element, and disposed to intercept the beets discharged from the screening element for the separation of trash from the beets, the roller being spaced from the discharge end of the screening element for the passage of the trash exclusive of the beets or parts thereof.

5. Apparatus for the separation of dirt

and trash from sugar beets, comprising a screening element consisting of series of rotary agitating units, and means for rotation of the units constantly in one direction only to effect a propulsion and screening of the beets, and an auxiliary separating element including a roller disposed to intercept upon its peripheral surface beets discharged from the screening element for the separation of dirt and trash from the beets and spaced from the end of the screening element, for the passage of trash exclusive of the beets or parts thereof, and means for rotation of the roller in a direction opposite to that of the units.

6. Apparatus for the separation of dirt and trash from sugar beets, comprising a screening element consisting of a frame, series of agitating units rotatable on the frame, and means for rotation of the units constantly in one direction only to effect a propulsion of material fed onto the element, to a point of discharge, and an auxiliary separating element including a roller disposed to intercept upon its peripheral surface beets discharged from the screening element for the separation of trash from the beets, and means for rotating the roller in a direction opposite to that of the units of the screening element, the units being arranged relative to each other and the frame, and the roller being arranged relative to the screening device to leave narrow spaces adapted for the passage of loose dirt and trash exclusive of beets or parts thereof.

7. Apparatus for screening sugar beets, comprising a screening element movable constantly in one direction only to effect a propulsion and screening of the beets, and an auxiliary separating element, including a plurality of spaced rollers disposed to successively intercept upon their peripheral surfaces beets discharged from the screening element, and means for rotation of the rollers in a direction opposite to that of the movement of the beets from the screening element.

8. Apparatus for screening sugar beets, comprising a screening element movable constantly in one direction only to effect a propulsion and screening of the beets, an auxiliary separating element disposed in inclined relation to said screening element and including a roller disposed to intercept beets discharged from the screening element in the direction of such inclination, and means for rotation of the roller in a direction opposite to that of the movement of the screening element and of the beets from the screening element, and means for the vertical adjustment of the auxiliary separating element thereby to vary its inclined relation to the screening element.

9. Apparatus for screening sugar beets, comprising a screening element consisting of a series of rotary agitating units and means

for rotation of the units in the same direction, and an auxiliary separating element including a frame movable about the axis of rotation of the last agitating unit of the screening element into various inclined positions relative to said screening element, a rotary element on the frame disposed to intercept beets discharged from the screening element in the direction of such inclination, means for rotating the element in a direction opposite to that of the agitating units, and means for vertical adjustment of the frame thereby to vary its inclined relation to the screening element.

10 10. Apparatus for screening sugar beets, comprising a screening element movable constantly in one direction only to effect a propulsion and screening of the beets, an auxiliary separating element including a series of rollers, rotatable in a direction opposite to that of the screening element and disposed in inclined relation to the screening element to successively intercept upon their peripheral surfaces beets discharged from the screening element in the direction of such inclination, 20 for the separation of trash from the beets, and means for varying the inclination of the series.

11 11. Screening apparatus comprising a series of agitating units each consisting of a 30 rotary shaft, and agitating members on the shaft, each having a hub and radial curved spokes, the members on any one shaft being arranged in staggered relation to each other, whereby the spokes of each alternate member on the shaft are opposite the spaces between the spokes of adjoining members on the same, said hubs being individually unrestricted free for a limited lateral displacement with relation to each other.

40 12. Screening apparatus comprising a series of agitating units each consisting of a rotary shaft, and agitating members on the shaft, each having a hub and radial curved spokes, the members on any one shaft being arranged in staggered relation to each other, whereby the spokes of alternate members on the shaft are in alinement between the alinement of the spokes of the other members on the same, said hubs being individually free 50 for a limited lateral displacement with relation to each other.

13. Screening apparatus comprising a series of agitating units each consisting of a rotary shaft, and agitating members on the shaft, each having a hub and radial curved spokes, the members being mounted for rotation with the shaft while being individually, unrestrictedly free for a limited lateral displacement with relation to each other.

60 14. Screening apparatus comprising a series of agitating units each consisting of a rotary shaft of angular section, and agitating members, each having a hub and radial curved spokes, the individual hubs of the 65 members being unrestrictedly and loosely

fitted on the shaft in spaced relation to each other.

15. Screening apparatus comprising a series of agitating units each consisting of a rotary shaft, and agitating members on the shaft, each having a hub and radial curved spokes, the members being mounted for rotation with the shaft while being individually, unrestrictedly free to wobble laterally with relation to each other.

70 16. Screening apparatus comprising a series of agitating units each consisting of a rotary shaft, and agitating members on the shaft, each having a hub and radial curved spokes, the members on any one shaft being arranged in staggered relation to each other, whereby the spokes of each alternate member on the shaft are opposite the spaces between the spokes of adjoining members on the same, and the units being relatively disposed so that the arms of adjoining units are in lapping relation to each other, said hubs being individually free for a limited lateral displacement with relation to each other.

75 80 85 In testimony whereof I have affixed my signature.
